UNITED STATES PATENT OFFICE

122,908

DESIGN FOR A PICTURE PROJECTOR SLIDE MOUNT

Bruno Stechbart, Chicago, Ill., assignor to The Bell & Howell Company, Chicago, Ill., a corporation of Illinois

Application August 2, 1940, Serial No. 94,161

Term of patent 14 years

To all whom it may concern:

Be it known that I, Bruno Stechbart, a citizen of the United States, residing at Chicago, in the county of Cook and State of Illinois, have invented a new, original, and ornamental Design for a Picture Projector Slide Mount, of which the following is a specification, reference being had to the accompanying drawing, forming a part thereof.

In the said drawing—

I claim:

The ornamental design for a picture projector slide mount, as shown.

BRUNO STECHBART.
